ELECTRIC SWEEPER

Original Filed Dec. 12, 1930

UNITED STATES PATENT OFFICE

1,968,530

ELECTRIC SWEEPER

Ward Leathers, Haworth, N. J., assignor to The Quadrex Corporation, a corporation of Connecticut

Application December 12, 1930, Serial No. 501,873
Renewed December 22, 1933

2 Claims. (Cl. 15—8)

The primary object of my invention is to produce an electric sweeper for high speed sweeping purposes as counterdistinct to vacuum-cleaning.

I accomplish this purpose by means of a motor-driven rotary sweeper, reversing the direction of rotation of the brush as the sweeper is operated to and fro. In order that the dirt may be disposed of, in better manner than in a carpet sweeper, for example, I have added a rotary suction fan to the motor shaft, and disposed of the dirt in any of the several manners outlined in my co-pending applications.

Such a sweeper performs the function in the most efficient manner of the push broom or the carpet sweeper.

In order to set forth my invention in terms so clear that all those familiar with these arts may readily understand, I have prepared the following specification to which I have added a drawing of which—

Figure I is a partial lateral cross-section of the sweeping mechanism.

Figure II is a partial horizontal cross-section of the same.

Figure III is an end view of the sweeper mechanism.

Figure IV is a detail.

In Figure I, 1 is a motor-suction unit showing the motor-cover in dotted lines, surrounded by an outer housing which carries the dirt-laden air upward to a proper disposal. These principles are more fully set forth in my co-pending patent applications Nos. 491,415—563,503—563,507—501,876—501,875—493,068—489,281—488,794—481,407—474,584—501,874—472,703—501,877. I have here shown the motor-suction unit supported on the handle, but it is equally practical to apply my sweeper mechanism to a motor unit supported on the floor in conventional manner such as shown in my application for Letters Patent No. 501,875. The part 2, shown as a die-casting, provides a cover for the motor-suction fan and an inlet for the dirt-laden air at the center, in the usual manner. It further provides two brackets 3, cast integral therewith or joined thereto. To the casting 2 is suitably attached a stamped brush housing 4. The brush housing has joined to it a flap 5 for covering the center opening to the motor-suction unit. A pulley 6, on the motor shaft drives a friction pulley 7, pinioned in the brackets 3, by means of a belt 8. The friction pulley 7 drives, by friction, an idler pulley 9, also operatively supported by the lugs 3, or extensions thereto. Frictional engagement between the pulleys 9 and 7 may be maintained

by any suitable adjustable or yieldable means, as illustrated, 9 is held frictionally to 7 by means of a spring 11, one end of which is latched to a yoke 12', riveted to the lugs 3, and the other end impinging against the shaft of the pulley 9. A rotary brush 12 has rigidly attached to its shaft 13, a friction pulley 14. The brush is supported at its ends on a member supported by the housing 4 and the pulley 14 is so disposed with respect to the pulleys 7 and 9 that a slight fore or aft movement will bring the pulley 14 into frictional engagement with one or the other of these driving means. The housing 4 may be continued on its undersurface in any desired manner, as at 15, for the production of a suitable brushing area and air inlet 16.

Theoretically, this sweeping device differs basically from the motor driven vacuum-sweeper, with the latter, two operating principles must be compromised, the one is a necessity for a considerable measure of vacuum, or low pressure, in order to abstract dirt from carpet pile or directly through the carpet, and the other, a movement of a reasonable stream of air as a dirt carrying agent. In my motor-driven sweeper, there is no vacuum required for cleaning purposes, the suction unit being used solely for providing a stream of dirt carrying air.

In Figure II, which is a horizontal cross-section of the central and end portions of the rotary brush mechanism, the pulley 18 supports the belt 8. 18 and 7 are made integral, 7 preferably covered with a frictional, yieldable surface, such as rubber or felt. The yoke 12 may be riveted, or otherwise joined, to the lugs 3, or the supports for the pulleys may be devised in any other suitable way. As shown, in Figure II, somewhat diagrammatically, the boss 19 in the yoke 12' is turned in with a round hole for the support of the shaft of the pulley 9. The boss 20 is turned in with a horizontal slot allowing the free movement in the fore and aft direction of the said shaft. The spring 11 holds the pulleys 7 and 9 in operable engagement. The shaft 13 of the brush is held in socket bearings 21. The socket 21 is rigidly attached to a bent part 22 (see Figures III and IV), which part carries a floor roller 23.

Figure III is an end view of the outside of the brush mechanism. Part 22 is shown rotatively joined to the housing 4 at 24. This hinge may be provided in any manner, but I have preferred to show it as a boss on 22, fitting neatly into a depressed socket in the housing 24, and held therein by a spring 25. When the springs

25, one on either end of the brush housing, are raised free from engagement with 22, the parts 22, together with the rollers 23, and the brush 12, may be completely and immediately removed 5 from the cleaner.

The part 22 is more clearly set forth in Figure IV. A rigid mounting is provided in the outer portion for the support of the idler roller 23. A socket 21 is rigidly attached to the inner portion. 10 Since the end of the housing 4 is disposed between the inner and outer portions of 22, the roller 23, is well supported both top and bottom and the socket 21 is firmly held in place.

In operation, as the cleaner is pushed forward, the roller 23 furnishes sufficient back-drag 15 to engage the pulleys 14 and 7, thus driving the brush 12 in a forward sweeping motion. When the cleaner is drawn backward, 14 engages 9, reversing the direction of the brush 12 and permitting it to sweep in a relative forward motion.

Having set forth my invention in clear terms, I wish it understood that the principles involved are those that may be applied in many and 20 various forms of design without departing from 25 the spirit thereof.

I claim :

1. In a suction cleaner, in combination, two power-operated driving-pulleys rotating in opposite directions; a nozzle; a rotary brush within said nozzle supported for back and forth movement relatively to the mouth thereof in accordance with the forward and backward movements of the cleaner; said brush having a cylindrical pulley-portion which alternately engages said oppositely rotating driving pulleys, one at a time, in accordance with the forward and backward movements of the brush. 80

2. In a suction cleaner, in combination, two power-operated driving-pulleys rotating in opposite directions; a nozzle; a rotary brush and an oscillatory support therefor on the nozzle, said support having floor-engaging wheels and permitting back and forth movement of the brush relatively to the mouth of the nozzle in accordance with the forward and backward movements of the cleaner; said brush having a cylindrical pulley-portion which alternately engages said oppositely rotating driving-pulleys one at a time, in accordance with the forward and backward movements of the brush. 85 90
